COMBINED FLUORESCENT LAMP AND CLOCK

Fred Mugnai, Chicago, Ill., assignor to Art Specialty Co., Chicago, Ill., a corporation of Illinois

Application April 4, 1950, Serial No. 8,955

Term of patent 7 years

(Cl. D48—20)

To all whom it may concern:

Be it known that I, Fred Mugnai, a citizen of the United States, residing at Chicago, in the county of Cook and State of Illinois, have invented a new, original, and ornamental Design for Combined Fluorescent Lamp and Clock, of which the following is a specification, reference being had to the accompanying drawing, forming a part hereof.

In the drawing—

Fig. 1 is a front perspective view of a combined fluorescent lamp and clock showing my new design; and

Fig. 2 is a rear perspective view thereof.

The dominant features of my design are shown in solid lines.

I claim:

The ornamental design for a combined fluorescent lamp and clock, as shown and described.

FRED MUGNAI.
